UNITED STATES PATENT OFFICE.

JOHN TURNER, OF UXBRIDGE, ENGLAND, ASSIGNOR TO THE RUBBER PATENTS LIMITED OF ORB WORKS, OF COWLEY, ENGLAND, A CORPORATION OF GREAT BRITAIN.

PLAYING-BALL CASE.

1,002,789.

Specification of Letters Patent.

Patented Sept. 5, 1911.

Application filed August 12, 1910. Serial No. 576,897.

To all whom it may concern:

Be it known that I, JOHN TURNER, a subject of His Majesty the King of Great Britain, and a resident of Uxbridge, in the county of Middlesex, England, have invented a certain new and useful Improvement in Playing-Ball Cases, of which the following is a specification.

This invention relates to an improved case for playing balls such as footballs, water polo balls, and the like of the kind wherein the foundation of the case consists of several sections of rubber coated or proofed textile fabric such as canvas, stitched together and suitably strengthened by means of one or more layers of similar material.

Heretofore footballs having cases of the kind above described have been open to the objection that they were too resilient and lively in play, indeed a dry leather case ball is sometimes open to this objection. Further it has been found that the seams in the canvas foundation and the strengthening pieces of what are termed "rubber" balls usually placed around the bladder opening in the casing, as at present constructed, form hard portions which interfere with the bound of the ball and are dangerous to the players, the seams also tend to wear through the outer rubber covering very rapidly, these defects being chiefly due to the fact that the building up materials are applied or principally applied upon the outside of the canvas shape.

Now this invention has for its object to provide an improved fabric proofed case whereby the various defects mentioned above are overcome, the finished ball having an even wall and being of uniform softness without hard portions, and having if desired a resilience even less than that of a dry leather balls, and approximating to the resilience of a damp leather ball which as is well known is preferably in play.

Further advantages will be apparent from the following description:—According to this invention the building up or strengthening is performed upon the inner surface of the canvas or fabric shape, a smooth outer surface being obtained, in which the seams are preferably slightly recessed to avoid the wear thereon. Further, throughout the various steps of the manufacture,

care is taken not to cure the rubber contained in the built up case, but when the case is completed a layer of cured rubber is laid or formed upon the outside thereof—for example, the layer may be of uncured rubber which is cured *in situ*.

In carrying out the invention a canvas shape or foundation is formed by stitching together several suitably shaped sections preferably of rubber coated heavy textile fabric, such as cotton canvas, preferably cut on the bias to insure even stretching, a slit or mouthpiece being left for the insertion of the bladder and the projecting seams of the sections being upon the outside of the shape. A strengthening piece for the mouthpiece is then separately made in the following manner:—A strip preferably of rubber proofed canvas having a slit corresponding to the slit in the canvas foundation has a piece of rubberized thread laid thereon, said thread being laid preferably around and around the slit until the fabric is practically covered. A second piece of proofed canvas also having a slit is then laid upon the surface of the rubberized thread and the two pieces of canvas are then stitched together the stitches extending preferably transversely across the slits and in parallel lines and being continued over the slits so as to partially close same and hold the edges together. The flap or tongue usually employed for closing the bladder opening is then stitched to the strengthening piece which is then ready for attachment to the canvas shape. A bladder is then inserted in the canvas shape and the strengthening piece solutioned or stitched to the mouthpiece slit thereon a few stitches in said strengthening piece being cut to allow the tube of the bladder to project. The shape is then inflated causing the seams to stand out upon the outer surface thereof. These outstanding seams if desired are then bound with suitable strengthening strips and the various sections between said seams except preferably for a small portion around the mouthpiece, are covered with one or more shaped layers of canvas or the like if a multi-ply ball is required and of cloth, felt or other suitable deadening material, until the case is of the desired thickness, the material then standing slightly above the outer edges of the seams. This strengthening and deaden-

ing material is preferably put on slack. The inflated case is now placed in a mold of somewhat larger size than same and is further stretched by the application of heat 5 and extra air pressure (applied through a pipe passed through the mold into the bladder) for about one minute, causing the strengthening and deadening material to be flattened down flush with the edges of the 10 seams. Such pressure may amount to say about 100 lbs. per square inch or more. The case is now removed from the mold and the bladder deflated and withdrawn. While still soft and hot the case is turned inside 15 out by the aid of the mouthpiece the stitches across same being cut for this purpose. Thus a case having a perfectly smooth outer surface and even walls is produced, the building up material together 20 with any slight unevenness that may exist being on the inside of the case. It is quite possible, however, if due care is exercised in the above operations, to produce a perfectly smooth inner surface also. The bladder is 25 again inserted and the case inflated and its outer surface then covered with cured or uncured rubber in any suitable manner, the case being then inserted in a steam jacketed or like mold for the purpose of producing a 30 suitable design or marks to represent stitching or otherwise upon its outer surface. A pressure of a hundred pounds or more is desirable for this purpose. Or the outer surface, of the case may be coated with a rubber solution or a mixture of rubber and gutta percha 35 solutions and suitably shaped pieces of sheet rubber with solutioned edges may be applied to each section the whole being cured *in situ* or before applying same in any suitable manner. For example—the pieces may 40 be cured in a press before being applied. The eyelet holes for lacing up the ball may be punched in the cover through the strengthened mouthpiece portion when said cover is 45 finished.

In strapping over the seams before laying on the strengthening material as before mentioned, it is preferable to employ strips of canvas cut on the straight and not upon the 50 bias, as when the case is turned inside out the straps refuse to stretch and tend to hold the seams in, thus forming grooves or recesses at the point of the seams on the outer surface whereby the wear is taken upon the edges of 55 said grooves or recesses and not upon the seams themselves which are moreover rendered less prominent.

It is possible to form a 3 or even 4 ply cover by the above described method and in 60 forming a 3-ply cover for example, instead of laying the canvas on each section of the case between the outstanding seams, said canvas may be applied over two sections at a time, from the side of one seam, over the 65 next seam to the bottom of the next, as here-

inafter described, the felt or other material being applied and the case finished as before described.

To enable the invention to be fully understood it will now be described by reference 70 to the accompanying drawings, in which:—

Figure 1 is a cross sectional view of the distended canvas shape after the sections have been sewn together and before being turned inside out showing the outstanding 75 seams thereon, and Fig. 2 is a side view of same partly collapsed, Figs. 3 and 4 are plan views of details of the two portions comprising the strengthening strip for the mouthpiece, drawn to a larger scale. Fig. 80 5 is a cross sectional view of a 2 ply case showing the canvas shape inside out and built up with two layers of strengthening and deadening material, that is in the present instance one further ply of canvas or the 85 like and one layer of felt or the like. Fig. 6 is a cross sectional view of a 3 ply case also inside out, that is in the present instance two further plies of canvas or the like and one layer of felt or the like. Fig. 7 is 90 an enlarged sectional view showing a method of binding the seams of the canvas shape.

Referring first to Figs. 1 and 2, the canvas shape, shown turned inside out, is formed of six sections *a*, in this case of a 95 single ply proofed canvas or material, the stitched edges of which form the outstanding seams *b* *b'* *b''* *b'''* *b⁴* *b⁵* and *c* is the slit or mouthpiece through which the bladder is introduced and withdrawn, said opening 100 being shown as already strengthened by the strip *c'*.

Figs. 3 and 4 show in plan view the method of building up the strengthening piece *c'* for the mouthpiece *c*; *d* being a 105 piece of proofed canvas having a slit *e* and *f* a piece of rubbered thread preferably laid around and around said slit and nearly covering the canvas. A similar piece of canvas *g* having a slit *h* is laid on top of the thread *f* and the two pieces are stitched together by a series of preferably parallel lines of stitches *i*, which may extend transversely 110 across the slit as shown in Fig. 4. The usual flap or tongue *k* may be then stitched on and the strengthening piece stitched and preferably solutioned around the cut opening or mouthpiece *c* the slits of course coinciding, see Fig. 2. A strengthening piece built 115 in this manner is soft and pliable and does not produce a hard portion on the surface of the ball as heretofore.

In Fig. 5 two layers of felt or cloth or other suitable material *l* are shown. They may be one ply of canvas or the like and a 125 layer of felt applied to the canvas sections and filling the space between the seams, a space however being left around the mouthpiece *c*.

Fig. 6 shows a method of forming a 3 ply 130

- canvas case in which pieces of canvas *m* are cut to the size of two sections *q* of the case and overlapped around said case, one portion of each piece being secured upon a section *q* of the canvas shape, the other portion of the piece extending over the seam as at *q'* and being secured upon the top of the next piece *m* as shown, the foundation thus consisting of 3 ply canvas. The mouthpiece *c* is strengthened as described and the spaces between the seams are then filled in with strips of felt or cloth *o*, and the case, pressed heated turned and finished as hereinbefore described.
- 15 Fig. 7 shows a seam *b* having a strengthening strip *p* stitched or otherwise bound around, preparatory to building up the case, said strip being preferably cut on the straight so that when the case is turned, the stitched seams will each form a slight recess upon the outside of the case as hereinbefore described, the wear being taken on the edges of the recess.
- 20 What I claim is:—
- 25 1. As a new article of manufacture a rubber proofed fabric playing ball case in the completed state of which the rubber is in the uncured state and which has an outer coating of cured rubber.
- 30 2. As a new article of manufacture a rubber proofed fabric playing ball case comprising in its completed state layers of uncured rubberized fabric and cured rubber the latter being on the outside of the case.
- 35 3. As a new article of manufacture a rubber proofed fabric playing ball case having in its completed state all the strengthening and deadening materials on the inside thereof, all the rubber being in the uncured state
- with the exception of an outer coating of 40 cured rubber.
4. As a new article of manufacture a rubber proofed fabric playing ball case in which the rubber is in the uncured state and which has an outer coating of cured rubber and a strengthening piece around the mouthpiece composed of two pieces of proofed fabric stitched together and having slits therein and a layer of rubber proofed thread between. 45
5. As a new article of manufacture a rubber proofed fabric playing ball case comprising layers of uncured rubberized fabric and cured rubber the latter being on the outside of the case and a strengthening piece around the mouthpiece composed of two pieces of proofed fabric stitched together and having slits therein and a layer of rubber proofed thread between. 50
6. As a new article of manufacture a rubber proofed fabric playing ball case having all the strengthening and deadening materials on the inside thereof, all the rubber being in the uncured state with the exception of an outer coating of cured rubber, 65 and a strengthening piece around the mouthpiece composed of two pieces of proofed fabric stitched together and having slits therein and a layer of rubber proofed thread between. 70

In testimony whereof I have hereunto set my hand in the presence of two subscribing witnesses.

JOHN TURNER.
